United States Patent Office.

THOMAS STANDRING, OF FORT RICHMOND, NEW YORK.

Letters Patent No. 81,823, dated September 1, 1868; antedated July 6, 1868

IMPROVED BELTING.

The Schedule referred to in these Letters Patent is making part of the same.

TO ALL WHOM IT MAY CONCERN:

Be it known that I, THOMAS STANDRING, of Fort Richmond, in the county of Richmond, and State of New York, have invented a new and improved Belting, &c.; and I do hereby declare that the following is a full, clear, and exact description thereof, which will enable those skilled in the art to make and use the same, reference being had to the accompanying plate of drawings, and to the letters of reference marked thereon, forming part of this specification.

This invention relates to a new and improved method of constructing belting, or traces, or other straps, now made of leather only, or of any one material, whereby the strength of the same is greatly increased.

It consists of a thin layer of steel or other suitable metal, cemented between two layers of leather or other suitable material, of less width than said layers, so that said metallic layer may be securely fastened by the edges of the straps being sewed together.

In the accompanying drawings—

Figure 1 represents a longitudinal section of my invention, taken in the line $z z$, fig. 2.

Figure 2 represents a plan view of the same.

Figure 3 represents a cross-section of the same, taken in the line $y y$, fig. 2.

Similar letters of reference indicate corresponding parts.

A is the belt or trace.

a is one of the layers or straps of leather.

e is the other layer or strap of leather.

a' is a strip or plate, of steel or other metal, between the layer a and the layer e.

S are the stitches, by means of which the parts or layers a and e are sewed together.

R are rivets, by means of which all the parts are secured together.

The belting or trace A is constructed of three parts or layers, a a' e. The part or layer a and the part or layer e are of leather, or other suitable material, the same as now in common use. Between the part a and the part e is a thin sheet or layer of steel or other metal, a', either tempered or not. Said sheet or layer is made narrower than the parts or layers between which the same is placed, so that two parts or layers a and e may be sewed together without passing the stitches through the metallic layer a', leaving the metallic layer a' between the rows of stitches on either edge of the belt or trace A, and also between the two parts a and e, as shown in the drawing, and as above described.

Said metallic sheet or layer a' is cemented to the parts or layers a and e by any common cement, so that the same is prevented from working between the parts a and e. Still further to secure the same, all the parts are firmly riveted together by the rivets R, as shown in the drawing.

The advantages of the above construction over belting or traces now in use are, that the strength of the same is thereby greatly increased, and the hooks used for fastening two ends of a belt together, are not liable, as now, to break out.

Having thus described my invention, I claim as new, and desire to secure by Letters Patent—

As a new article of manufacture, the belting, consisting of the solid sheet of steel a', clamped between the leather parts a e by the central rivets R, and prevented from loosening by being cemented to such parts, as herein shown and described.
